UNITED STATES PATENT OFFICE

ARCHIE H. BECHTOL, OF DAYTONA BEACH, FLORIDA, AND WALTER A. TRATSCH, OF CHICAGO, ILLINOIS

DESIGN FOR A DISPENSING CABINET

Application filed June 3, 1932. Serial No. 43,974. Term of patent 14 years.

To all whom it may concern:

Be it known that we, ARCHIE H. BECHTOL and WALTER A. TRATSCH, both citizens of the United States, residing at Daytona Beach, Florida, and Chicago, Illinois, respectively, have invented a new, original, and ornamental Design for a Dispensing Cabinet, reference being had to the accompanying drawing, forming part thereof.

Figures 1, 2 and 3 are respectively a top plan view, a front elevation and a side elevation of the cabinet, showing our new design.

We claim:—

The ornamental design for a dispensing cabinet as shown.

In testimony whereof we affix our signatures.

ARCHIE H. BECHTOL.
WALTER A. TRATSCH.
